TYPOGRAPHICAL MACHINE

John W. Bittner, Bellerose, N. Y., assignor to
Intertype Corporation, Brooklyn, N. Y., a corporation of New York

Application May 23, 1941, Serial No. 394,791

5 Claims. (Cl. 199—33)

This invention relates to improvements in typographical machines of the general organization represented in Letters Patent No. 436,532 wherein circulating character bearing matrices stored in a grooved magazine and released therefrom in response to manipulation of a keyboard are assembled in line, the composed line being presented at the front of a slotted mold into which molten type metal is injected at the rear to form a slug having on its upper edge the characters represented by the matrices, and the matrix line thereafter being transferred to the distributing mechanism of the machine which includes a so-called channel entrance divided into a plurality of passages by fixed solid body partition plates for guiding the individual matrices while in free flight between the distributor proper and their respective grooves in the magazine.

As well known, these machines are called upon to handle fonts of matrices in a wide variety of sizes with the result that both thin and thick bodied matrices are required to pass between adjacent partitions of the channel entrance. For this reason it is customary to provide in association with the partitions one or another form of auxiliary matrix guiding means such as thin flexible blades or spring plates bent to project somewhat into the passages between adjacent partitions and weak enough to be deflected by and thus allow free passage of the thick matrices yet strong enough to direct thin matrices to one side of a passage and lead them in upright position to the point where the usual projecting lugs or ears thereon enter the grooves in the magazine.

Heretofore, whatever the form of the auxiliary guiding means employed, it has been constituted by a separate part or parts suitably secured to each partition as by welding and as exemplified, for example, in Letters Patent No. 1,349,488. Such arrangements, however, are objectionable in modern machines because the thickness added to the partition by the extra part decreases the available space between adjacent partitions to such extent as to retard and sometimes even obstruct the passage of certain size matrices and thus prohibit the use of certain maximum size matrix fonts that otherwise might be run in the machine. As a matter of fact, and as will be evident to those skilled in the art, the matter of a few thousandths of an inch restriction in the width of certain of the channel entrance passages has been found to be an objectionable limitation. Moreover, once such auxiliary guiding means added to one side of a partition is bent or de-

flected away from the solid body of the partition plate at an angle or curvature necessary to the proper guidance of certain matrices it is difficult if not impossible in many instances to change its angle of deflection to suit other matrices without mutilating the thin metal as by twisting or distorting its form and in this or other ways rendering it a hinderance rather than an aid to the proper guidance and smooth passage of matrices.

10 The present invention is intended to overcome the foregoing and other objectionable conditions and to this end contemplates as an auxiliary matrix guide a spring finger or blade constituted preferably by a strip only partially severed out of the partition proper, the opening formed in the partition by the portion thus freed enabling the latter to be flexed back and forth freely about the connection it retains with the partition and across the plane of the latter when it is desired to alter its disposition relative thereto, and said opening also allowing the freed portion to be depressed wholly within the planes of the sides of the partitions whereby to preserve the entire width of the space therebetween for the passage 15 of matrices. Broadly viewed, therefore, the invention contemplates this or any equivalent construction that will give one or both of the aforesaid distinct advantages.

Another feature of the construction according to the present invention is the disposition and width of the cut-out in the partition plate and of the guide finger itself relative to the usual upper and lower curved plates of the channel entrance which form the top and bottom walls of the matrix passages. As will be seen the boundaries 20 or edges of the guide fingers and of the openings in the partitions are so spaced from the top and bottom plates that matrices bearing like characters but differing in thickness in different size 25 fonts will pass without danger of wedging or of entering the opening or of clogging the entrance.

A still further feature of the invention is the simplicity and economy of the proposed construction both in manufacture and maintenance, 30 the making and assembling as heretofore of a number of separate parts (actually ninety-one for main magazine entrances and thirty-six for side magazine entrances) being eliminated, and the ease and possibility of making proper 35 adjustments of the guide fingers being of material advantage in saving time and securing smooth operation of the machine in service.

In the accompanying drawing, the invention has been illustrated in preferred form and by way of example but obviously variations may

be made in the form and arrangement of the parts and the mode of application thereof without departing from the spirit of the invention. It is to be understood, therefore, that the invention is not limited to any specific form or embodiment except insofar as specified in the claims.

Referring to the drawing:

Fig. 1 is a vertical section taken through the upper part of a conventional typographical machine with the improved form of matrix guide and partitions according to the invention applied to the channel entrance.

Fig. 2 is a fragmentary plan view in the direction of the arrows 2—2 in Fig. 1 with the top plates of the magazine and channel entrance removed to show the relation of the matrix guide and partition of the invention to the magazine grooves and entrance passages.

Fig. 3 is a fragmentary elevation viewed from the lower end of the channel entrance in Fig. 1.

Fig. 4 is a fragmentary section taken on the line 4—4 in Fig. 1.

Referring to Fig. 1, the invention is shown as applied to a conventional form of typographical machine having a single distributor, the latter comprising as usual the combination ribbed distributor bar 1 and the set of rotary screws 2 for conveying the matrices M along the bar 1 until they reach a point at which, according to the character they represent, the matrix tooth and ribbed bar combinations agree and thus allow the matrix to drop off the bar and fall by gravity into the channel entrance passage leading to the proper storage place in the magazine 3. The magazine 3 comprises upper and lower plates provided on their inner opposed faces with grooves in which engage the usual edgewise projecting lugs on the matrices so as to sustain the latter in upright edgewise position in the magazine in well known manner.

For simplicity sake only, the magazine 3 here shown is of the so-called side or auxiliary style in which the grooves 4 run parallel from the top to the bottom of the plates as distinguished from the grooves in main magazines which converge from top to bottom of the usual trapezoidal shaped plates of such magazines. As will become evident, however, to those skilled in the art the improved form of partition and matrix guide according to the invention is equally applicable as to construction and performance when associated with either style of magazine. It is to be noted that the grooves 4, as usual, are tapered or flared toward their upper ends so as to present a widened opening for the reception of the matrix lugs as the matrices discharge from the entrance passages into the magazines.

The channel entrance comprises upper and lower downwardly curved plates 5 and 6 respectively separated by intermediate flat plates or partitions 7 disposed edgewise between them and dividing the entrance into a series of passages 8 for conducting matrices dropped off the distributor bar to the respective grooves 4 in the magazine. The partitions 7 are suitably anchored in place at predetermined spaced intervals (usually unequally spaced, as shown, according to the body thickness of the different matrices to be accommodated between them) as by lugs 9 adapted to project through slots in the upper and lower plates 5 and 6 and to accommodate longitudinal keeper rods 10 bearing against the outer sides of the plates. The general form and arrangement of the parts thus far described is substan-

tially the same as employed in commercial machines so that further detailed explanation thereof seems unnecessary for present purposes.

According to the present invention, the channel entrance partitions and the auxiliary matrix guiding means necessary for the proper handling of both thin and thick bodied matrices are integral parts, the auxiliary guides preferably being formed directly from a portion of the partitions. Thus, referring particularly to Fig. 1, there is formed within the boundaries of the edges of each partition 7 and at a substantial distance from said edges (as by punching, sawing, milling or otherwise) spaced narrow rectilinear slots 12 extending longitudinally of the partition plates, and between these slots (at the ends thereof toward the lower end of the plates) there is formed a short cross slot 13. The slots 12 are substantially equal in length and converge toward each other, as shown, and in the direction in which they converge they diverge respectively from the nearest adjacent entrance plates 5 and 6. It is to be pointed out, however, that this specific formation and disposition of the slots 12 and 13 has merely been found by experiment to be generally advantageous but that non-converging slots, slots with a slight curvature, and slots disposed at a uniform distance from one or both of the plates 5 and 6 are also contemplated since they are equally suited to producing auxiliary guides possessing the features and advantages of the present invention.

The provision of the slots 12 and 13 results in producing out of the material along the central region of the partition plates relatively narrow flexible strips 11 only partially severed from the plates and remaining joined thereto at their upper ends as clearly shown in Fig. 1. The slots 12 and 13 obviously produce an opening in each partition into which the strip 11 may lie flatwise and be confined totally within the planes of the side faces of the partition and such opening provides clearance around the sides and free end of the strip for the latter to pass through in both directions when flexed about its connection with the body of the partition for purposes of adjustment, as will later be explained. By forming the cross slot 13 somewhat back from the lower end of the partition the connecting portion 14 aids in maintaining the rigidity of the end of the partition plate. The cross slot, however, may be dispensed with if desired and the slots 12 formed all the way through to the lower end of the partition.

It will now be evident that the strips 11 constitute the necessary flexible auxiliary matrix guide fingers without in any way increasing the over-all thickness of the partitions themselves and consequently without decreasing the space available between adjacent partitions for the passage of matrices. Moreover, by forming the guide fingers directly out of the partitions in the manner set forth the fingers may be flexed freely in both directions through the openings in the partitions (see Fig. 4), thus affording a facility heretofore impossible for adjusting the guides to change the amount of projection of any individual guide into the matrix passage it is intended to serve. Such ability to alter the setting or disposition of each guide relative to its partition is an important consideration in adapting a machine to handle both the thin and thick matrices of the minimum and maximum size fonts, and it will be apparent that the freedom provided for flexing the guides back and forth

through the openings in the partitions (as by pressing against them a suitable tool projected into an adjacent passage) enables changing their setting without danger of twisting or distortion.

The action of the auxiliary guide fingers 11 on thick and thin matrices is clearly indicated in Figs. 2 and 3 which show the guides bent or deflected to an inclined position relative to the partition plates, the guides being disposed so as to project different extents into the matrix passages of the entrance according to the varying widths of the respective passages and the range of thickness of like-character matrices intended to be accommodated. Thus, the moderately thin matrix M¹ as it passes the guide finger 11 is pressed by the finger toward one side of the passage 8 which latter is wide enough to handle matrices of much greater thickness when necessary and requires the guide 11 as a means for holding the thinner matrix M¹ in upright position so that its lugs will enter the grooves in the magazine. The set or inclination of the guides 11 and their flexibility in each instance is such that a thin matrix M¹ or a thick matrix M² may pass without hesitation, the thick matrix M², as shown, pressing the guide nearly all the way back into the opening from which it is formed out of the body of the partition plate. It will be obvious that a matrix slightly thicker than the matrix M² would press the guide completely back into the opening in the partition where the guide would lie wholly within the planes of the side faces of the partition. Thus as a distinct feature broadly contemplated by the invention there is provided integral with the entrance partitions auxiliary matrix guides so associated with and related to the partitions as to preserve for the passage of matrices the total width of the spaces defined by the actual side faces of the partitions. This advantage in itself might, of course, be obtained in alternative ways such as the obvious method of insetting the auxiliary guide in an elongated shallow panel or recess milled or otherwise formed part way into the thickness of the partition from one side face thereof, the guide being constituted by a separate thin strip made integral with the partition as by welding it at one end to the bottom wall of said recess. Or the partition may be provided with a complete opening (similar to the opening formed by slots 12 and 13) for the purpose of permitting flexing of an auxiliary guide in both directions and the guide, constituted by a separate thin strip then being made integral with the partition as by welding it at one end to a thinned portion of short extent formed as a continuation of one end of the opening. These and various other alternatives will readily suggest themselves to those skilled in the art and will be included within the scope of the appended claims.

The proportions as to thickness, width and length of the auxiliary guide fingers 11 are such that they are strong enough to deflect and guide the thinner matrices in upright posture to one side of a wide passage as required yet weak enough to be depressed by the thicker matrices to the extent necessary for their unhindered passage. The disposition laterally of the guide fingers 11 and the openings produced by forming them directly out of the material of the partitions is such that with respect to matrices passing at either side of a partition any portion of the configuration of the matrix such as the lugs

thereof, the notched bottom edge, or the body proper may pass by the guide or over the opening without danger of wedging on the former or entering the latter. Thus, in Fig. 1, a matrix M³ is represented by dot-dash lines in two positions in its flight through a passage 8 in the channel entrance. The dot-dash line L traces the average line of contact with a partition of the outermost corner of the lower lugs of a matrix M³ appropriate to any given passage 8 in the entrance. In other words, taking the smallest size font practical to run, for example, in the standard auxiliary magazine here shown, the thinnest matrices appropriate to the respective passages 8 may tilt or tip over sidewise as they drop into a passage but in no case will the line of contact of the lugs of any such matrix fall so low (lower than the line L) as to enter the opening in the partition to the right of the matrix.

The slightly tapered shape of the guide 11 and the opening affords a simple way of keeping the inner or connected end of the guide and opening relatively narrow (to afford the desired degree of flexibility) and confined laterally to the central region of the width of the partition and adjacent passages, and at the same time enables the guide to be made wide enough at its free end to provide an adequate bearing surface for forcing and sustaining the passing matrices in upright condition.

Having described my invention, what I claim is:

1. In a typographical machine, the combination of a channel entrance for guiding matrices from the distributor to a magazine and having spaced partitions forming matrix passages between them, with auxiliary matrix guiding means constituted by portions partially severed from the respective partitions and bendable about their unsevered connections therewith into the matrix passages at either side of the partitions.

2. In a typographical machine, the combination of a channel entrance having spaced partitions forming between them passages for the guidance of matrices and auxiliary matrix guiding means adapted to project into said passages, said guiding means being formed by portions partially severed from the respective partitions and producing corresponding openings therein for the flexing therethrough in opposite directions of said partially severed portions.

3. The combination as set forth in claim 2, characterized by the fact that the portions partially severed from the partitions and the openings produced thereby extend longitudinally of the partitions and matrix passages and are confined laterally throughout their extent to a relatively narrow portion of the central region of said partitions and passages.

4. The combination as set forth in claim 2, characterized by the fact that the portions partially severed from the partitions and the openings formed thereby extend longitudinally of the partitions and passages, and by the further fact that the longitudinal edges of said partitions and openings are located at such distance from the corresponding outer edges of the partitions proper as to permit matrices tilted edgewise in the passages between partitions to pass without wedging thereon.

5. In a typographical machine for handling fonts of matrices differing in size, the combination of a channel entrance having partitions unequally spaced apart and forming between them passages for accommodating the different ma-

trices in a font of the maximum size capable of entering the passages, and flexible matrix guides adapted to deflect to one side of the entrance passages matrices belonging to fonts of less than maximum size, said matrix guides being formed by portions partially severed directly from the respective partitions and flexible about their un-

3 severed connection therewith into and out of the planes of said partitions whereby upon deflection thereof by matrices of the maximum size such matrices may occupy the full width of the passages as defined by the sides of the partitions.

JOHN W. BITTNER.
